UNITED STATES PATENT OFFICE

105,366

DESIGN FOR A BAG FOR AUTOMOBILES

Hugo Neuburger, Los Angeles, Calif.

Application April 28, 1937, Serial No. 69,010

Term of patent 14 years

To all whom it may concern:

Be it known that I, Hugo Neuburger, a citizen of Switzerland, residing at Los Angeles, in the county of Los Angeles and State of California, have invented a new, original, and ornamental Design for a Bag for automobiles, of which the following is a specification, reference being had to the accompanying drawing, forming a part thereof.

Figure 1 is a perspective view of a bag for automobiles, showing my new design.

Fig. 2 is an end elevational view thereof looking from the left toward the right of Fig. 1.

Fig. 3 is an elevational view of the rear side of the bag.

Fig. 4 is a front elevational view of my novel bag, but with the pocket flap raised so as to disclose the opening into the interior of the bag, otherwise hidden.

The cross-hatching applied only to part of the bag is meant to designate surface shading and represents material that is continuous throughout the several areas, and the stippling indicates a material of contrasting character or color and is meant to be continuous throughout the surface to which it is applied.

I claim:

The ornamental design for a bag for automobiles as shown and described.

HUGO NEUBURGER.
